HIGH EXPLOSIVE SHELL

Frank Robertson, Jonesboro, Tenn.

Application May 11, 1933, Serial No. 670,571

3 Claims. (Cl. 102—29)

This invention relates to an improved high explosive shell and seeks, among other objects, to provide a device of this character which will be particularly effective against aircraft.

5 Another object of the invention is to provide a high explosive shell which will carry a fuse, which fuse may be of sufficient predetermined length to permit explosion of the shell at a desired time.

10 A further object of the invention is to provide a high explosive shell which will, after explosion, send particles through the air throughout a relatively large area so that aircraft flying in vicinity will be destroyed or crippled.

15 And a still further object of the invention is to provide a high explosive shell wherein the plunger employed will be locked against accidental shifting into engagement with the cap, but which will be capable of ready engagement with the cap when the shell is fired from the gun.

20 A further reading of the following description will disclose objects not hereinbefore mentioned.

My invention is illustrated in the accompanying sheets of drawings wherein Figure 1 is a vertical sectional view of my improved shell showing the shell as it would appear when loaded and ready for insertion into a cartridge.

Figure 2 is a vertical sectional view of my high explosive shell and shows the shell as it would appear before loading, and with the fuse removed,

Figure 3 is a top plan view of my improved shell,

Figure 4 is a transverse sectional view taken on the line 4—4 of Figure 2, looking in the direction indicated by the arrows, and

Figure 5 is an enlarged fragmentary detailed sectional view showing the time fuse and cap employed.

40 Referring now more particularly to the accompanying drawings, the numeral 1 indicates the body portion of my improved shell. As best seen in Figures 1 and 2 of the drawings, the upper end of the shell is concave, as indicated by the numeral 2, and is provided with an axially disposed recess 3. Leading axially and longitudinally of the body portion 1 from the recess is a circular cylindrical passage 4 which is formed, immediately below the recess, with an annular groove

45 5. Leading outwardly to the periphery of the body portion and connecting said outer surface of said body portion with the groove 5 is a relatively small passage 6. The passage 6 is preferably disposed at right angles with respect to the passage 4. The body portion 1 is recessed

axially throughout its major portion to define a wall 7 and a tubular boss 8 axially of said body portion. A circular space is therefore defined between the wall 7 and the boss 8, and said wall 7 is formed with annular spaced substantially V-shaped grooves 9 which serve to slightly weaken the wall so that when the wall is shattered, the edges of the particles will be defined by the limits of the grooves. The wall 7 is reduced at 10 and is formed with internal threads 11 throughout 10 the reduced portion. An annular groove 12 is formed exteriorly of the body portion 1 and is disposed nearly opposite one of the grooves 9.

5 Carried in the recess 3 is a plunger which is indicated in general by the numeral 13. The 15 plunger includes a head 14 which is circular shaped and is adapted snugly but shiftably to fit within said recess 3. The head 14 is provided at its upper surface with a pocket 15 which is substantially cup-shaped to define overhanging 20 edges 16. The cup-shaped pocket, with the overhanging flange, is particularly effective as all of the force working against the plunger will be utilized and none of it will be permitted to deflect from the sides of the plunger. Formed integrally 25 on the head 14 is a plunger shank 17 having an annular groove 18 near its lower end. Formed integrally on the plunger shank 17 is a firing pin 19 which is substantially conical in shape. The passage 6 is adapted to be filled with 30 lead or other soft metal and said soft metal is adapted to flow within the groove 5 and within the groove 18 formed in the shank 17. Said lead functioning for normally locking the plunger in a position out of engagement with the cap, to 35 be described hereinafter.

The boss 8 is internally threaded and screwed into said internally threaded portion is a sleeve 20. The sleeve 20 is provided at its inner end with a cap 21. The cap may be of any desired 40 construction. Screwed into the sleeve 20 at its outer end is a tube 22 and carried in the tube is a fuse 23, the inner end of which is secured to the cap 21 so that detonation of the cap will ignite the fuse. The fuse may be of any length, 45 depending upon the time desired for exploding the shell. The fuse is placed in the tube so that the sparks on the burning fuse will not come in contact with the high explosive carried within the shell until the desired time.

50 Screwed into the body portion 1 and within the reduced wall 10 is an outer shell portion 24. The outer shell portion is provided with a relatively thick outer end 25 and, as best seen in Figure 2 of the drawings, the outer shell portion is 55

provided throughout its length with spaced annular weakening grooves 26 and vertical weakening grooves 27. Substantially conical pockets 28 are formed in the relatively thick outer end portion 25. It should be understood that, while I have shown the shell portion as being formed with four of the vertical grooves 27, any desired number of said grooves may be utilized. The inner end of the shell portion is reduced to provide a shoulder 29 and a relatively thin wall 30 which is externally threaded. A gasket 31 is seated on the shoulder 29 and a gasket 32 is seated at the inner end of the reduced wall 30. The gaskets will, of course, prevent moisture from entering the shell and will therefore protect the high explosive carried therein. The numeral 33 indicates the high explosive which fills the interior of the shell portion and the annular space of the body portion 1. The explosive may be the well known Trinitrotoluene, commonly known as TNT. It will be seen that the high explosive completely fills all of the grooves and the conical pockets throughout the entire area of the interior of the device.

25 After the shell has been placed in a loaded cartridge and the cartridge is exploded and the shell is driven from the gun, the force of the explosion within the cartridge will be directed against the outer end of the plunger by the concaved surface of the rear end of the shell and concentrated in the pocket 15 by the overhanging edges 16 of its walls to drive the plunger inwardly towards the forward end of the passage 4 so that the firing pin 19 will engage and detonate the cap 21. The force of the explosion will be sufficient to cause the plunger to shear the lead in the registering grooves 5 and 18 as the plunger is urged forwardly into position to detonate the cap but the plunger cannot accidentally move forwardly towards the cap. When the cap has been detonated the fuse 23 will, of course, be ignited and will burn its way within the tube 22 until the end of the fuse is reached, when said spark makes contact with the high explosive within the shell and sets it off. The explosion of the TNT within the shell will, of course, break the shell into a number of pieces, as stated. The edges of the pieces will be defined by the grooves 26 and 27 and also the conical pockets 28. The force of the explosion will drive the pieces of shell in every direction and, as is obvious, should an airplane be anywhere near the exploded shell, the fragments will, in all probability, come in contact with the airplane and will cripple it and bring it to the earth.

55 It is quite obvious that the device is not limited to use in combating airplanes but it would be equally effective in reducing forts. This device could also be used on the sea.

60 It is believed that a reading of the foregoing description will clearly bring out the fact that

I have devised a high explosive shell which will be characterized by the greatest efficiency and utility.

Having thus described my invention, I claim:

1. In an explosive shell, a hollow body having a concaved rear end face and being formed with a recess at the center of the concaved rear end face and a bore extending forwardly from the center of the recess into the interior of the hollow body, an explosive substance filling said body, a cap in the inner end of said bore, a plunger having a head slidably received in said recess and a shank extending forwardly from the head and slidably received in the bore and adapted to fire the cap when moved forwardly into engagement with the cap, the head of said plunger having its outer face formed with a pocket having overhanging marginal walls whereby force of an explosion discharging the shell and concentrated by the concaved rear face of the shell will be confined in the pocket and drive the plunger forwardly into engagement with the cap, and means for normally holding said plunger in a set position with the inner end of its shank spaced rearwardly from the cap but permitting the plunger to be moved forwardly when subjected to the said force applied to its outer end.

2. In an explosive shell, a hollow body having annular walls and thick front and rear end portions, the rear end portion being formed with a bore, a cap in said bore, the front end portion being formed with internal pockets spaced transversely from each other and extending longitudinally of the front end of the body and being open at their inner ends and tapered toward their front ends, walls of said body to the rear of the pockets being formed with internal grooves, the pockets being appreciably deeper than the grooves, the grooves and pockets serving to weaken the walls and thick front portion of the body and permit the same to be easily broken into small parts when subjected to force of an internal explosion, an explosive substance filling said body, and means operating in the bore for firing said cap.

3. In an explosive shell, a hollow body having a concaved rear end face and being formed with a bore extending forwardly from the concaved rear face and opening into the interior of the hollow body, an explosive substance in said body, a cap in said bore, a plunger slidably received in the bore and adapted to fire the cap when moved forwardly into engagement with the cap, the exposed rear end of said plunger being formed with a pocket having overhanging walls whereby force of an explosion discharging the shell and concentrated by the concaved rear face of the shell will be confined in the pocket and drive the plunger forwardly into engagement with the cap.

FRANK ROBERTSON.
